UNITED STATES PATENT OFFICE

WILLIAM C. HIERING, OF NEWARK, NEW JERSEY, ASSIGNOR TO J. E. MERGOTT COMPANY, OF NEWARK, NEW JERSEY, A CORPORATION OF DELAWARE

DESIGN FOR A CIGARETTE-PACKAGE HOLDER

Application filed November 8, 1929. Serial No. 33,371. Term of patent 14 years.

To all whom it may concern:

Be it known that I, WILLIAM C. HIERING, a citizen of the United States, residing in the city of Newark, in the county of Essex and State of New Jersey, have invented a new, original, and ornamental Design for a Cigarette-Package Holder, of which the following is a specification, reference being had to the accompanying drawing, forming a part thereof.

In the drawing:

I claim:

The ornamental design for a cigarette package holder, as shown.

WILLIAM C. HIERING.
